UNITED STATES PATENT OFFICE.

THOMAS J. PILLIOD, OF SWANTON, OHIO.

CABINET.

Application filed November 19, 1926. Serial No. 149,429.

My invention consists in a new and useful improvement in cabinets and is designed to provide a cabinet adapted to contain all of the requisites for a game of auction bridge 5 for four or more players. The particularly novel and useful feature of my device is the construction of the interior of the cabinet to provide suitable receptacles for the various articles of equipment required by the 10 players. The parts of the cabinet are so designed and related as to afford ample facilities for packing all the game requirements in a very handy and attractive way. The special advantage of my improved 15 cabinet is that a hostess, entertaining players for one or more table of auction bridge, may place a single cabinet upon each table, assured that when the cabinet has been properly packed the players at each table are provided with all the requisite equipment for 20 the game, so that no embarrassment will be occasioned by any omission of any part of the equipment.

Referring to the drawings:

25 Fig. 1 is a front elevation with the lid open.
Fig. 2 is a plan view of Fig. 1.
Fig. 3 is a longitudinal section of my gaming case, with the lid closed.
30 Fig. 4 is a cross-section of my device, with the lid closed.

Referring more particularly to the drawings, 1 represents the body portion of the case, composed of the side walls 1^a, 1^a and 35 the end walls 1^b, 1^b, with the lid 2 and the bottom 3. The lid 2 is provided with a strap 4 for resiliently holding auction bridge tally cards 5 and score pads 6. Hinges are denoted by 7 and a cloth or other suitable 40 material is provided and adapted to serve as a cover check 8 to hold the lid in a pre-determined relation to the body portion 1 when the lid is opened. A filler element 9 is disposed adjacent each of the end walls 45 1^b, 1^b of the case, and extends between the side walls 1^a, 1^a. These filler elements 9 are composed, respectively, of two side walls 10 and two end blocks 11 therebetween. The end blocks 11 are provided respectively 50 with bores 12 adapted to receive pencils 13 therein with strings 13^a attached to each.

The walls 10 and blocks 11 of each of

these elements 9 are so designed and related as to form a compartment 14 in each element 9 which is suitable for containing a case for 55 a deck of auction bridge cards 15.

The filler elements 9 serve to form a compartment 16 which is of suitable dimensions for containing a box of candy 17.

It will be noted that the pencils 13, cases 60 for card decks 15 and candy box 17, extend above their respective compartments 12, 14, and 16, thus making it easy to extract them from their normal position in the case.

A name plate 18 and ornamental straps 65 19 and handles 20 and lock clasp 21 are provided for beauty and service.

The inner faces of the lid 2 and bottom 3 are provided with resilient paddings 22, and 70 23, respectively, thus forming two cushion bodies between which the candy box 17, tally cards 5 with their strings 5^a and the score pads 6 are resiliently held when the lid 2 is closed.

It will be understood that I do not limit 75 my invention to the precise structure shown and described as it is apparent to anyone skilled in the art that I may make changes and alterations as fairly come within the scope of the appended claims.

Having described my invention, what I 80 claim as new and desire to secure by Letters Patent is:—

1. In a cabinet, the combination of four 85 walls; and filler elements, each adjacent one of two of the walls and extending between the other two walls, and provided with a cavity adapted to receive a deck of playing cards, and also provided with bores adapted to receive pencils therein, the disposition of the said filler elements relative to the walls being such that there is provided a central receptacle adapted to receive a candy box 90 therein.

2. In a cabinet, the combination of two 95 side walls and two end walls; and a filler element, adjacent each end wall and extending between said side walls, comprising two side walls and two end blocks, the side walls and end blocks of each filler element being so disposed as to provide a receptacle adapted to contain a deck of playing cards, each of said end blocks being provided with a bore adapted to receive a pencil therein.

3. In a cabinet, the combination of a body portion comprising a receptacle; a cover comprising a receptacle; a resilient padding applied to the bottom of the body portion; 5 a second resilient padding applied to the cover; and means for retaining articles in the cover, the parts being so proportioned

and related that the two resilient paddings are adapted to co-act with the articles in the cover to firmly hold a container placed in 10 the receptacle in the body portion.

In testimony that I claim the foregoing as my own, I affix my signature.

THOMAS J. PILLIOD.
